PRECAST REINFORCED TILE BEAM AND
SPAN TILE FLOOR STRUCTURE

Charles T. Bridgman, Des Moines, and Henry Giese, Ames, Iowa, assignors to Iowa State College Alumni Association, Incorporated, Ames, Iowa, a corporation of Iowa

Application October 27, 1936, Serial No. 107,838

3 Claims. (Cl. 72—66)

Our present invention relates to a floor structure involving the use of pre-cast reinforced tile beams and span tile.

More particularly, it is the purpose of our invention to provide in such a structure beams made of pre-cast tile. Each such tile has a central body portion and has at its opposite sides below its top, upwardly opening channels to receive concrete and steel reinforcing.

Thus it is our object to provide a floor structure having inverted T-beams, each made of tile of the kind above described, laid end to end with mortar joints, and having the channel on each side substantially filled with concrete in which is reinforcing steel.

The span tile project above the beams. A thin slab of concrete is placed on this beam and span tile structure. The concrete flows into the ends of the span tile and covers the top and upper side portions of the beams, whereby we bond the entire structure together in such manner as to provide maximum load carrying strength in what is a T-beam floor structure.

With these and other objects in view, our invention consists in the construction, arrangement and combination of the various parts of our pre-cast reinforced tile beam and span tile floor structure, whereby the objects contemplated are attained, as hereinafter more fully set forth, pointed out in our claims, and illustrated in the accompanying drawing, in which:

Figure 1 is a perspective view of one of the tile used in making the inverted T-beam which forms a part of our floor structure.

Figure 2 is a perspective view of our floor structure illustrating various steps in the construction; and

Figure 3 is a detail, sectional view taken on the line 3—3 of Figure 2, of a completed floor.

In the accompanying drawing, we have used the reference character A to indicate generally the tile used in making the beam. The tile A comprises a central body portion having the form of an ordinary hollow tile, having the top 10, sides 11, and the bottom 12, and having the central opening 13, extending lengthwise through the tile.

Projecting laterally from the bottom 12 in opposite directions are the extensions 14, which terminate in upwardly extending walls 15.

There is thus formed at the side of each central body member an upwardly opening channel, such as is indicated at 16.

The tile is preferably formed with lengthwise corrugations 17 on its top 10, side walls 11 and

in the upper surface of the extensions 14 and the inner faces of the walls 15.

Referring now to Figure 2, our improved floor structure includes beams B formed from the tile A in the manner hereinafter more fully described, 5 span tile C, and a concrete slab D.

One of the advantages in our structure arises from the fact that the beams B may be made on the job by placing a number of tile A end to end on any suitable support, such as a plank, with 10 the adjacent ends of the tile "buttered" with mortar, then concrete 18 is poured into the channels at the sides of the beam, and steel reinforcing rods 19 are properly embedded in the concrete 18.

It will, of course, be understood that the size of the tile beam may be varied and that the size of the reinforcing may also be varied depending upon the job under construction.

The beam B can be made of the desired length. 20 After the concrete is cured, the beams may be placed in properly spaced position in the building.

Span tile C are set on mortar beds on and between successive beams B, as illustrated in Figure 3. The span tile may be hollow tile of such 25 length and size as may be selected for the purpose. Ordinarily they will vary from twelve to twenty-four inches in length.

It will be observed that another important advantage in this structure lies in the arrangement, 30 whereby the ends of the span tile C have positive support on the horizontal shoulders formed by the concrete 18 in the channels 16.

Thus we have the advantage that the span tile do not depend on a vertical bond for support, 35 but have the solid shoulder or shelf thus afforded. The parts are so proportioned and assembled that when the span tile have been laid, they project above the tile of the beams B enough to allow access to the passages through them. The span 40 tile are also so laid that concrete may flow between their ends and the walls 11 of the tile A of the beams B.

Next soft concrete is poured on top of the span tile and beams as indicated at D.

The concrete of the slab D flows down between the ends of the span tile C into the spaces between such ends and the side walls of the tile A down to the concrete 18.

Some of the concrete D flows into the ends of 50 the span tile C as indicated at 22 in Figure 3. There is thus afforded an intimate and very strong bond between the concrete of the slab D and the span tile and the beams B.

An important advantage in the structure here- 55

inbefore described lies in the free adaptability of the structure for making various spans to carry a variety of loads. With five variables, adjustment can be had for getting any needed strength, 5 for example, for structures ranging from residences to warehouses.

It is an easy matter to vary the length of the beams, to use reinforcing of different strength, to vary the length of the span tile and consequently the spacing of the beams, to vary the 10 depth of the span tile and to vary the thickness of the concrete topping, and thus adapt the floor structure to the particular job. All this can be done with one size of beam tile.

15 We have made and supervised a great many experiments as a result of which design tables have been prepared, which are available for builders.

By following these tables, the builders can construct floors, ceilings, or the like for various 20 spans or live loads. Furthermore this construction has come into practical use in residence and commercial buildings, and has the approval of numerous city engineers for the building codes of their cities.

25 Another reason for the acceptance of our floor structure is the economy with which it can be built.

The use of forms and shoring is entirely eliminated.

30 By the particular construction here illustrated, we have been able to produce a composite reinforced tile and concrete T-beam floor structure with a minimum of weight and hence of cost. By our design and use of material we have been able 35 to utilize the strength of the materials most effectively and have reduced the material and weight in the zone of the neutral axis.

We claim as our invention:

1. In a floor structure, a series of beams, each 40 comprising tile laid end to end with mortar joints, each tile having formed at its opposite sides below its top laterally projecting, upwardly open-

ing channels, the channels being substantially filled with reinforced concrete, hollow span tile laid upon and between the successive beams with their ends resting directly on the horizontal shoulders thus formed, and concrete above the beams and span tile bonded to the interior of the span tile and to the first-named concrete and to the upper side walls and tops of the beams. 5

2. A reinforced tile beam comprising a series of similar tile laid end to end, with mortar 10 joints, each tile comprising a hollow central body, having a top, spaced sides and bottom, lateral extensions projecting horizontally in opposite directions from the bottom, having at their outer edges vertical upstanding flat-topped walls terminating short of the top of the tile to form channels at the sides of the tile, the channels at the sides of the beam having therein concrete, forming continuous bodies, and metal reinforcing 15 rods in the respective bodies of concrete. 20

3. A reinforced tile beam comprising a series of substantially similar tile laid end to end with mortar joints, each tile comprising a hollow central body with a top, spaced sides and a bottom and lateral extensions projecting horizontally in 25 opposite directions from the bottom and terminating in upstanding flat-topped flanges shorter than the central body whereby channels are formed at the sides of the tile, said beam being combined with span tile having their ends resting upon said flanges, the span tile being hollow with their open ends adjacent the beam and extending above the beam, reinforcing rods in said 30 channels near the bottoms thereof, concrete filling said channels and arranged between the span tile and the beam and projecting into the open ends of the span tile, the span tile being arranged close together side by side and covered by concrete. 35
